JOHN F. HARRISON, JR., OF LADDONIA, MISSOURI; CROCKETT J. HARRISON
ADMINISTRATOR OF SAID JOHN F. HARRISON, JR., DECEASED.

INCUBATOR-TRAY.

1,300,957.

Specification of Letters Patent. Patented Apr. 15, 1919.

Application filed April 15, 1918. Serial No. 228,651.

To all whom it may concern:

Be it known that I, JOHN F. HARRISON, Jr., a citizen of the United States, residing at Laddonia, in the county of Audrain and 5 State of Missouri, have invented certain new and useful Improvements in Incubator-Trays, of which the following is a specification.

This invention relates to trays, and more 10 particularly to a tray for holding the eggs in an incubator.

One of the main objects of the invention is to provide a tray of the character stated of simple construction and operation by 15 means of which the eggs to be incubated may be secured against excessive movement so as to prevent breakage thereof. A further object is to provide a tray by means of which the eggs may be held securely in 20 position so as to permit the tray to be turned for the purpose of turning simultaneously all of the eggs contained within the tray, thus effecting a material saving of time and labor. Another object is to provide 25 a tray composed of two sections movable toward and away from each other, these two sections being provided with means for supporting and resiliently gripping the eggs so as to prevent movement 30 thereof when the tray is inverted for the purpose of turning the eggs. A still further object is to provide a tray the effective height which may be readily varied to suit different sizes and kinds of eggs. 35 Further objects will appear from the detailed description.

In the drawings:

Figure 1 is a top plan view of a tray constructed in accordance with my invention,

Fig. 2 is a fragmentary side view,

Fig. 3 is a fragmentary sectional view taken at right angles to Fig. 2.

This tray is of rectangular or box-like construction, and is formed of the upper section 1 and the lower section 2. This upper section is provided, adjacent its top, with a rectangular frame 3, to which is secured a piece of screening wire 4 or other suitable fabric, 45 this wire being tightly stretched. An end board 5 is secured to each end bar 6 of top frame 3 and projects a considerable distance below the same. A side board 7 is secured to each side bar 8 of top frame 3 and projects below the same a distance corresponding

to the width of the end board 5. These side and end boards coöperate to produce a box frame which fits about the top frame 3 so as to completely inclose the same and extends a considerable distance below this top frame. 60 Adjacent each end of the top frame 3, a runner strip 9 is secured to facilitate insertion of, and removal of, the tray into or from an incubator. Lower section 2 is of similar construction to the upper section 1 65 being provided with the lower frame 3^a having the fabric cover 4^a, end boards 5^a, and side board 7^a.

The two sections 1 and 2 are mounted in spaced superposed relation and are oppositely disposed so as to form a casing for containing the eggs, as shown in Fig. 3. Adjacent each end of each side board 7 of the upper section 1, is secured a substantially rectangular plate 10. This plate is provided, at its upper end, with a finger 11 disposed at right angles thereto which engages over the upper edge of side board 7. This plate carries a vertically disposed head 12 having a depending reduced stem 13 which 70 is threaded to provide a securing screw. The threaded stem 13 fits snugly through an aperture through the horizontal arm 14 of an angle bracket 15 whose vertical plate is secured on the side board 7^a of the lower 75 section 2 and has a finger extending below the lower edge thereof. A securing nut 16 is threaded on shank 13 above arm 14, a similar nut 17 being threaded on to the shank beneath this arm. The nuts 16 and 80 17 coöperate to adjust the upper section toward and away from the lower section and to secure the two sections in adjustment so as to prevent relative movement 85 thereof. By this means, I provide an adjusting and securing device adjacent each corner of the tray by means of which the two sections may be moved toward and away from each other so as to cause the fabric coverings or screens 4 and 4^a to be 90 brought into gripping engagement with the eggs 18 placed in the tray.

In using this tray, the eggs to be incubated are placed in the lower section 2 so as to be supported by the screen 4^a thereof 105 in the ordinary manner, the eggs being placed closely together and, if there is any vacant space this may be filled by any suitable material such as excelsior, raw cotton, or other material suitable for the purpose. 110

After the eggs have been placed in the lower section, the upper section 1 is then placed in position with the threaded stem 13 of the securing devices projecting through the arm 14 of the angle bracket. By means of the nuts 16 and 17, the upper section is then adjusted toward the lower section a sufficient distance to bring the screens 4 and 4^a into gripping engagement with the eggs contained between the two sections. The screens act to resiliently grip the eggs so as to securely retain the same in position, the resiliency of the screens preventing breakage of the eggs. It should be understood, of course, that the two sections should be adjusted so as to grip the eggs securely without exerting unnecessary pressure thereon. When the eggs have been placed in the tray, this tray is then inserted into the incubator in the ordinary manner. As above stated, to facilitate insertion or removal of the tray, strips 9 are provided adjacent the ends of top section above the frame 3. Similar strips 9^a are also provided adjacent each end of the lower section 2. When it is desired to remove any of the eggs from the tray to test for fertility, or for any other reason, the upper section may be readily removed for this purpose and replaced in the manner previously described when it is desired to reinsert the tray into the incubator. When it is desired to turn the eggs, as should be done at least every twenty-four hours during the period of incubation from the time of placing the eggs in the incubator to within three days of the time for hatching, that is during a period of eighteen days approximately, this may be readily accomplished by withdrawing the tray from the incubator and inverting it after which the tray may be then reinserted. By this means, I effect a great saving of time and labor in the turning of the eggs as all of the eggs contained within one tray may be turned at a single operation instead of being turned individually and by hand as is now the common practice. When the eggs pip, the upper section of the tray may be removed so as to permit the chicks to escape from the tray into the lower portion of the incubator.

It will be evident that there may be slight changes made in the construction and arrangement of the different parts of my in-

vention without departing from the field and scope of the same, and I intend to include all such variations, as fall within the scope of the appended claims, in this application in which a preferred form only of my invention is disclosed.

What I claim is:

1. In an incubator tray, an upper section of box-like construction provided in its upper end with a frame having a fabric closure member secured thereto and acting to close the frame, a lower section mounted beneath the upper section and provided adjacent its lower end with a frame to which is secured a fabric closure member, the fabric closure members of the two said sections acting to grip eggs placed within the tray formed by the sections so as to prevent movement thereof, and means for holding the frames in place; combined with plates secured to the exterior of said sections, the upper plates having fingers passing over the upper edges of the sections and the lower plates having fingers passing under the lower edges of their sections, arms projecting outward from the lower plates, heads projecting from the upper plates and having depending threaded shanks passing through said arms, and an adjusting nut on the shanks above and below said arms, for the purpose set forth.

2. In incubator trays, an upper section of box-like construction provided adjacent its upper end with a screen closure member, a lower section of box-like construction positioned beneath the upper section and provided adjacent its lower end with a screen closure member, angle brackets secured to said lower section adjacent the ends thereof, said angle brackets being provided with outwardly directed horizontal arms, heads secured to the upper section and provided with depending threaded stems inserted through openings provided through the horizontal arms of the said angle brackets, and securing and adjusting nuts threaded on the stems of said heads above and below the horizontal arms of the bracket members.

In testimony whereof I affix my signature in presence of two witnesses.

JOHN F. HARRISON, JR.
